(57) **CLAIM**

We claim the ornamental design for a vane for use in coverings for architectural openings, as shown and described.

DESCRIPTION

FIG. 1 is an isometric view of the vane of the present invention. FIG. 2 is a top plan view of the vane of FIG. 1, with a bottom plan view being a mirror image thereof.

FIG. 3 is a right end elevation of the vane of FIG. 1.

FIG. 4 is a rear elevation of the vane of FIG. 1.

FIG. 5 is a front elevation of the vane of FIG. 1; and,

FIG. 6 is a left end elevation of the vane of FIG. 1.
